UNITED STATES PATENT OFFICE.

ASA F. CORNELL AND GEORGE W. K. KING, OF COFFEYVILLE, KANSAS, ASSIGNEES OF
ONE-HALF TO ROY T. OSBORN, OF NEW YORK, N. Y.

FURNACE.

Application filed November 30, 1925. Serial No. 72,069.

Our invention relates more particularly to furnaces such as are employed for heating boilers, oil stills and the like. In such furnaces as heretofore commonly constructed, 5 the travel of the flames and products of combustion from the fire box is in one direction only so that the boiler or other object heated is unevenly heated throughout the operation, certain regions or portions thereof receiving or being subjected to the flames and gases while at their highest temperatures and other portions or regions thereof being subjected to the gases only after the latter have been considerably cooled. As a result 10 either the one portion of the boiler or the like is overheated or the other is inefficiently heated, or both, with the result that there is rapid deterioration in the part subjected to the highest temperature while the cooler 15 part remains in good condition and, furthermore, in the case of water boilers, there is excessive local deposition of lime and in the case of stills or boilers for oil or other organic matter there is apt to be local deposition 20 of carbon; the deposition in either case serving to more or less insulate the metal from the cooling effect of the contained liquid thus seriously increasing the destructive effect of the heat.

25 By means of our improved construction and the method of operation involved therein the boiler, still or other article being heated is evenly heated, thereby greatly prolonging the life thereof, and the heat developed by the combustion of the fuel is more efficiently and completely utilized.

30 In our improved furnace combustion chambers are provided at the opposite ends of the fire box or heating space beneath the boiler or the like and are alternately fired, 35 thus equalizing the heating effect at the respective opposite ends of the boiler, and the waste gases, after they have communicated their heat as far as practicable to the boiler or other object being heated, are conveyed 40 through regenerators or recuperators in which a large share of the residual heat contained therein is absorbed and returned to the air employed for combustion when the 45 operation of the furnace is reversed. We also provide means for automatically reversing 50 the furnace at even intervals and for accurately controlling the supply of air and the exhaust of waste gases such that maximum efficiency is provided with minimum

volumetric capacity. Other features and advantages of our invention will appear from the following detailed description and claims.

While we have shown and described our 60 invention as embodied in a battery of boilers it is to be understood that this specific disclosure is for the purpose of exemplification only and that the invention is not limited thereto but is defined in the claims, in 65 which we have endeavored to distinguish it from the prior art as known to us without, however, relinquishing or abandoning any portion or feature thereof.

In the drawings accompanying and forming 70 a part of this specification, Figure 1 is a front elevation of a battery of boiler furnaces embodying our invention, partly broken away and showing the interior in vertical longitudinal section; Fig. 2 a plan 75 partly in horizontal section; Fig. 3 a transverse vertical section on the plane of the line 3—3 of Fig. 1, parts being shown in elevation; Fig. 4 a plan of a detail on an enlarged scale, the stack being shown in horizontal section; Fig. 5 an elevation partly in 80 vertical section of a detail on an enlarged scale, and Fig. 6 an elevation of the same detail perpendicular to the plane of Fig. 5. Parts are identified by the same reference 85 characters wherever they occur in the several views.

In the particular embodiment of our invention chosen for exemplification thereof and shown in the figures, the boilers are represented at 6, three being shown in the battery, mounted on suitable settings 7. The boilers are shown as of an ordinary cylindrical form. Beneath each boiler within the setting is provided a space 8 for the flames 95 and hot gases with which space communicate two combustion chambers 9—9 arranged respectively at opposite ends of the boiler. The fire boxes are formed on their respective opposite sides with preferably inclined 100 openings 10 into which project burner nozzles 11. These nozzles are angularly adjustable and connected by branch pipes 12 with fuel mains 13 arranged longitudinally of the battery on opposite sides thereof. By 105 reason of this angular adjustability of the burners the flames may be directed as desired in the combustion chambers or into the fire box or heating space beneath the boilers. Each combustion chamber is connected 110

by a short vertical flue or opening 14 with a horizontal flue 15, there being two such flues, one on each side of the battery and extending substantially the length thereof but at a lower level. Beneath each flue 15 is a second or stack flue 16 and between the flues 15-16 of each pair are a nest or multitude of vertical tile pipe sections 17 which form the communication between said flues 15 and 16. In the particular construction shown the tile sections 17 rest upon the top arches 18 of the flues 16 and said arches are perforated as at 19 in registry with the tile sections so that proper communication between the flues 15 and 16 is provided.

The flues 16 are connected by branch flues 20 to a common stack flue 21 and the stack 22. Said flues 20 are also connected to an air inlet flue 23, the flues 20, 21, 23 meeting in a valve chamber 24 containing a butterfly valve 25 by means of which the respective flues 20 can be thrown alternately into communication with the stack flue 21 and the air inlet flue 23.

By reason of the construction thus far described the boiler furnaces are reversible, that is to say, air for supporting combustion and gas or other fuel may be first supplied to the combustion chambers on one side of the battery and burned therein for a desired interval and then combustion may be shifted to the set of chambers on the other side of the battery, the chambers being thus alternated in use. When combustion is taking place in the one set of chambers the products of combustion after passing through the heating chambers under the respective boilers escape through the combustion chambers on the other side of the setting and down through the openings 14, flue 15, tiles 17 and flue 16 to the stack. In passing in the small separated streams through the tiles 17 the greater proportion of the residual heat in the gases is communicated to the tiles so that the gases escape to the stack at a relatively low temperature and when the operation is reversed, the air in passing through said tiles on its way to the respective fire boxes is preheated to a high degree, so that the products of combustion passing from the chambers to the space beneath the boiler are highly heated to the required temperature with a minimum expenditure of fuel. The reversal of operation is effected by shifting the butterfly valve 25 and at about the same time changing the supply of fuel gas from the one set of combustion chambers to the other. Thus when the butterfly valve is in the position shown in Fig. 2 the air entering the inlet 23 will flow through the passage 20 in communication therewith and so to the corresponding flue 16 and the combustion chambers above the same, while at the same time the products of combustion passing down on the

other side of the battery enter the flue 16 and through the branch flue 20 flow to the stack.

Obviously by suitably arranging the burners in the respective combustion chambers more or less complete combustion may be caused to take place therein and it is preferable that the arrangement be such that combustion shall be completed therein in order to avoid the carrying of unburned material into the recuperator tile passages 17 and the flues and stack. The flames however may be shifted as desired by adjusting the burners. In order to heat the regenerators or recuperators in advance of putting the furnaces into operation or if desired to increase the temperature thereof and of the connected passages, we provide at 26 openings extending through the exterior wall of the setting into certain of the hollow tiles 85 or regenerator pipes and provide branch fuel pipes 27 from the mains 13, the ends of which project into the openings 26 at 28 and form burners, see Figs. 1 and 3. By igniting these burners the tiles and the passages beyond the same will be heated, as referred to above. Suitable valves are provided for controlling the fuel supply pipes 12 and 27. Obviously by thus providing for the combustion in the fire boxes and periodically reversing the direction of flow of the heating gases from the fire boxes so that the hot gases are alternately supplied to the opposite ends of the boiler or other object heated a much more uniform and even heating effect is obtained, thus preventing the rapid deterioration, deposition of lime, etc., which take place in the construction of the prior art where the heat distribution is uneven and certain regions or portions of the apparatus are subject to overheating if a sufficient firing is maintained.

In the preferred embodiment of our invention illustrated in the drawings, the reversal of operation described above is automatically effected, both the butterfly valve and the valve for controlling the supply of fuel to the mains being automatically reversed. In this construction we have shown the fuel supply valve as a rotary 3-way valve 110 29 having a port communicating with a supply pipe 30 and opposite ports communicating respectively with the pipes 31, 32 connected to the respective mains 13 on opposite sides of the furnace to which we have before adverted. The turning plug of the valve is constructed in an obvious manner to alternately throw the respective branch pipes 31-32 into communication with the supply pipe 30 and is mounted on the spindle 115 or revoluble stem 33 of the butterfly valve so that the two valves will swing together. The upper end of this spindle is provided with an arm 34 which is connected by a link 120 35 with a rod 36 of an actuating piston con- 130

tained in the cylinder 37, see Figs. 1, 4 and 5. The cylinder 37 is alternately supplied with a motive fluid, steam or the like, at opposite ends by means of a suitable slide valve 5 in the casing 38, mounted on the cylinder. This construction is so well known that description thereof is unnecessary.

The slide valve is operated from a rock shaft 39, see Figs. 1, 5 and 6, which is provided at its opposite ends with forked arms 40, 41. Above and between the respective arms are beveled pinions 42, 43, driven in reverse directions, as will presently appear, and each carrying a pin 44, 45 on its outside 15 face in a position to engage in the flaring space or crotch between the branches of the respective forks. The pinions are driven in opposite directions by an intermediate beveled pinion 46 and the pins 44, 45 are 20 so arranged that they will alternately engage the respective forked arms 40, 41 to alternately rock the shaft 39 first in one direction and then in the other, the intervals between the rocking movements being the 25 same so long as the pinions 42, 43 are revolved at uniform speed. The pinion 46 is mounted on the shaft 47, of a gear 48, and the latter is driven by a train of reducing gears 49, 50, 51 from a worm wheel 52, the 30 latter being turned by a worm 53 driven by a small electric motor 54.

The electric motor is constantly driven while the furnace is in operation and the reduction by means of the train of gearing 35 is such that the desired interval is permitted to elapse between each operation of the valve within the casing 35. Thus the fuel supply valve and the butterfly valve are shifted together at suitable intervals to reverse the firing of the furnace. Obviously 40 to increase or decrease the intervals between reversals it is merely necessary to suitably change the reducing gear described above. The turning plug is so ported that the fuel 45 is turned on at each reversal only after the butterfly valve has reached a position to cut off the air from the combustion chamber previously fired.

In order to regulate the supply of air 50 so that just the proper amount for perfect combustion with no substantial excess shall be supplied to the fire boxes, we provide the air inlet flue 23 with a gate valve 55. The position of this valve may be regulated by 55 means of a windlass 56 on the drums 57 of which are wound cables 58 connected to the respective opposite ends of the gate valve or damper. The shaft 56 of the windlass is provided with a worm wheel 59 which may be turned by means of a worm 60 to adjust the damper.

In order to control the escape of gases 60 to the stack and yet provide a free passage to the stack and prevent trapping of the hot 65 gases in the upper part of the horizontal

flue leading to the stack, we form the opening from said flue to the stack on an incline, as shown at 61, Fig. 1, and employ a damper or gate 62 which slides within a recess 63 below said flue. A windlass and connections 70 similar to those described in connection with the air damper are employed for adjusting the stack damper 62. By mounting the damper below the passage so that it will cut off the lower rather than the upper part 75 thereof when partially closed, we avoid trapping the hot gases and thus a much better draft is provided with the same capacities of flues and stack.

We claim:

1. In a furnace of the class described a boiler, a setting therefor including a heating chamber beneath the boiler, a combustion chamber at each end of the heating chamber and beyond the end of the boiler, burners 85 extending into the combustion chamber from opposite sides thereof, a flue communicating with each combustion chamber, an air inlet and a stack flue with which both of said flues communicate and valve mechanism 90 whereby said flues may be alternately cut off from the stack and air inlet.

2. In a furnace of the class described a boiler, a setting therefor including a heating chamber beneath the boiler, a combustion chamber at each end of the heating chamber and communicating therewith and beyond the end of the boiler, burners extending into the combustion chambers from opposite sides thereof, a flue communicating 100 with each combustion chamber, a regenerative means in each said flue, a stack and an air inlet also communicating with both said flues and valve mechanism whereby the said flues may be alternately cut off from the 105 stack and air inlet.

3. In a furnace of the class described a boiler, a setting therefor including a heating chamber beneath the boiler, a combustion chamber at each end of the heating chamber 110 and communicating therewith and beyond the end of the boiler, burners extending into the combustion chambers from opposite sides thereof, a flue communicating with each combustion chamber, a regenerative means in each said flue, a stack and an air inlet 115 also communicating with both said flues, valve mechanism whereby the said flues may be alternately cut off from the stack and air inlet, and means for automatically reversing 120 said valve mechanism.

4. In a furnace of the class described a substantially horizontal stack flue, a stack and a connecting flue inclined upward from said horizontal flue to the stack. 125

5. In a gas-burning furnace of the class described a stack flue, a stack, a damper controlling the passage of gases from the flue to the stack, said damper closing upwardly.

6. In a gas-burning furnace of the class 130

described comprising a substantially horizontal flue and a stack with which said flue communicates, a sliding damper for adjusting the opening between said flue and stack, 5 said damper being adjustable through an opening in the lower wall of the flue whereby the upper portion of the flue is unobstructed.

7. In a reversing furnace of the class described and in combination with the combustion chambers thereof, flues leading from said combustion chambers to a valve chamber, a stack, an air inlet communicating with said valve chamber, a valve in said chamber and an adjustable damper for regulating the 10 opening of the air inlet.

8. In a reversing furnace of the class described and in combination with the heating chamber and oppositely arranged combustion chambers thereof, a horizontal flue connected to the combustion chambers on each side of 20 said heating chamber, a second pair of flues respectively beneath the first mentioned flues, hollow tile connecting said flues and adapted to be heated by the products of combustion and to heat air passing there- 25 through, connections from the last mentioned flues to a stack and an air inlet and means for reversing said connections.

ASA F. CORNNER.
GEORGE W. K. KING.
